UNITED STATES PATENT OFFICE

CHARLES C. WILLIS, OF NEW BRUNSWICK, NEW JERSEY, ASSIGNOR TO JOHN WALDRON CORPORATION, OF NEW BRUNSWICK, NEW JERSEY, A CORPORATION OF NEW JERSEY

METHOD OF AND APPARATUS FOR FOLDING NAPKINS

Application filed July 21, 1931. Serial No. 552,275.

This invention relates to a method of and apparatus for forming paper napkins from a continuous sheet of material.

An important object of the invention is 5 the provision of a paper napkin for use in dispensing containers so folded that double thickness grasping portions are provided at each edge of the napkin without regard to which face of the napkin is disposed outwardly in the container and in which, furthermore, such double thickness grasping portions are disposed at both sides of the napkin so that they may be conveniently grasped with either hand.

10 A further object of the invention is the provision of an apparatus for use in folding such napkins, and more particularly in the modification of the structure shown in the prior application of John S. Burt, Serial 20 No. 495,259, filed November 12, 1930, for paper napkin embossing printing and folding machine, to enable napkins folded in this manner to be produced thereby.

15 These and other objects I attain by the construction shown in the accompanying drawings wherein, for the purpose of illustration, I have shown a preferred embodiment of my invention and wherein:

20 Fig. 1 is an end elevation of folding apparatus constructed in accordance with my invention;

Fig. 2 is a side elevation thereof;

25 Fig. 3 is a perspective of a portion of the sheet from which the napkins are formed, the dotted line indicating the line of first fold therein;

30 Fig. 4 is a perspective of the portion of the sheet after formation of such fold and showing by dotted lines the lines of secondary fold;

Fig. 5 is a perspective of the strip formed by the secondary folding, the dotted line indicating the line of transverse fold; and

35 Fig. 6 is a perspective view of the folded napkin.

40 Referring now more particularly to the drawings, the numeral 10 generally designates a pair of feed rolls by means of which a paper sheet S withdrawn from a suitable roll, not herein shown, is caused to pass down-

wardly over a plow point 11 which forms the primary central fold therein along a line approximately indicated by the construction line F' of Fig. 3. From the plow point the now folded sheet F. S. is drawn by said feed 55 rolls over the roller 12 about a roller 13 and through an edge folder 14, the sheet between the roller 12 and the feed rolls moving approximately horizontally. The roller 13 is approximately the same width as the width 60 of the folded napkin which it is desired to produce and which is of less width than the folded sheet F. S. produced as above described. The folder 14 is disposed between the feed rolls and roller 13, and turns back 65 the edges of the folded sheet F. S. upon lines indicated at F-2 and F-3 in Fig. 4 to produce a strip S. T. such as clearly shown in Fig. 5. This strip S. T. is then folded along the transverse line F-4 by a combined folding and cutting mechanism 15 which is preferably of that type illustrated in the prior application hereinbefore mentioned, including a rotating body 16 having pairs of jaws 17 between which the strip of Fig. 5 is inserted by a rotating tucking blade 18 associated with the rotating body 16. The rotating body 16 further embodies cutting blades 19 which coact with a stationary cutting blade 19-a to sever the now completely folded napkin illustrated in Fig. 6 from the remainder of the strip S. T. The fold 70 F-4 is preferably made in such direction that the reverted edges of the strip S. T. of Fig. 5 are disposed at the outer faces of the 75 folded napkin, its edges forming grasping portions 20 extending inwardly from opposite edges of the folded napkin without regard to which face of the napkin is inwardly disposed when the same is placed in 80 the container. Furthermore, these grasping portions since they project inwardly from opposite edges of the napkin are readily engageable from either side and by either hand, and such grasping portions, due to the fact 85 that the sheet is initially centrally folded, are of double thickness and, accordingly, afford sufficient strength to prevent tearing of the napkin as it is withdrawn from the 90 container.

The tucking blade 18 serves to insert the strip S. T. between the jaws 17 at the center of the terminal portion of the strip which is of a length equal to the length of the desired napkin. By mechanism not herein disclosed the free end of the strip is then blown back so that it trails from the jaws 17 in which it is engaged, the following knife 19 as it passes the stationary blade 19—a coacts therewith to sever the napkin from the strip.

Since the construction hereinbefore set forth is obviously capable of modification without in any manner departing from the spirit of my invention, I do not wish to be understood as limiting myself thereto except as hereinafter claimed.

I claim:

1. The method of producing folded paper napkins from a sheet consisting in folding the sheet with a plurality of longitudinal folds to produce a multilayer strip the edge portions of which are folded back on the strip at a common side thereof and have their edges spaced in a direction transverse to the strip and then transversely folding the strip with said side outwardly.

2. The method of producing folded napkins from a continuous sheet consisting in folding the sheet with a plurality of longitudinal folds to produce a multilayer strip the edge portions of which are folded back on the strip at a common side thereof and have their edges spaced in a direction transverse to the strip, then transversely folding the strip with said side outwardly at a point spaced from the end of the strip a distance equal to one-half the length of the desired napkin and finally severing the folded portion from the strip in alignment with the free edge of the folded portion.

3. In apparatus for folding napkins and the like, means for feeding a sheet comprising feed rolls, a horn over which the sheet is drawn by the feed rolls to thereby produce a central fold in the sheet, an edge folder between the feed rolls and said horn and including means for folding the edges of the sheet back upon the sheet prior to their passage through the feed roll to thereby produce a folded strip and a folder receiving the folded strip from the feed rolls and including means for transversely folding the strip at a point spaced from the end thereof and for severing the folded portion from the strip in alignment with said end after the fold.

4. In apparatus for folding napkins and the like, means for feeding a sheet comprising feed rolls, a horn over which the sheet is drawn by the feed rolls, a roll adjacent the horn and over which the folded sheet passes, a roller transversely spaced from the first-named roller receiving the folded sheet from said first-named roller, the last-named roller having a width less than the width of

the folded sheet and centrally engaging the same to thereby leave the marginal portions of the sheet free, an edge folder disposed between the last-named roller and said feed rolls and through which the folded sheet passes, said edge folder including means for reverting the edges of the folded sheet upon the sheet to thereby produce a folded strip which is creased by the feed rolls and means receiving the folded strip from the feed rolls for transversely folding the same and for severing the folded portion from the remainder of the strip.

CHARLES C. WILLIS.
